UNITED STATES PATENT OFFICE.

GEORGE A. MCLEAN, OF LITTLE ROCK, ARKANSAS.

CRATE OR BOX.

Application filed October 17, 1921. Serial No. 503,099.

To all whom it may concern:

Be it known that I, GEORGE A. MCLEAN, a citizen of the United States, and a resident of Little Rock, in the county of Pulaski and State of Arkansas, have invented a new and Improved Crate or Box, of which the following is a full, clear, and exact description.

This invention relates to improvements in crates, particularly to the type of crates or boxes commonly employed for shipping fruits and vegetables.

An object of the invention is to provide a crate of this character which can be folded so that the empty crates will occupy a very small amount of space.

A still further object is to provide a crate which will be light in weight, yet strong and durable in use, simple and practical in construction, and exceedingly inexpensive to manufacture.

With these and other objects in view, the invention consists in certain novel features of construction and combinations and arrangements of parts as will be more fully hereinafter described and pointed out in the claim.

In the accompanying drawings:

Figure 1 is a perspective view of the crate or box assembled;

Figure 2 is a similar view showing the crate disassembled and partially folded; and

Figure 3 is an enlarged view in section on the line 3—3 of Figure 2.

Referring in detail to the construction of my improved crate which is of rectangular boxlike formation, it will be seen that the side walls of the same consist of a plurality of longitudinal slats such as 1 secured at their ends to corner posts 2. The end sections or walls of the crate comprise vertical slats 3 connected at their upper and lower edges to cross pieces such as 4. The cross pieces extend appreciably beyond the slats and straddle the side walls of the box.

It will be noted that when the box is assembled, the side walls are arranged with the corner posts of the opposite walls presented towards each other and the cross pieces 4 straddling the walls are pivotally connected to the corner posts in any approved manner.

For the purpose of pivotally connecting the side walls and the end sections, I pref-

erably utilize nails such as 5, passing through the cross pieces 4 and into the tops or bottoms as the case may be of the corner posts 2. The cross pieces are bored to receive these nails. It will be seen that the crate may be readily folded until the corner posts of one side wall engage the intermediate portion of the other side wall at which time all of the walls of the box will be in a parallel plane. The walls are retained against folding by a box bottom which comprises a plurality of longitudinal slats 5' nailed or otherwise secured at their ends to cross pieces 6. A box top 7 similar to the box bottom is also provided for closing the crate.

For shipping or handling empty crates or boxes, the end walls and side walls are pivotally connected and assembled by use of the pivotal nails as above described. The tops and bottoms of the boxes or crates are handled separately until the crate is desired for use. The top and bottom sections may then be attached by driving a single nail through each corner of the top and bottom sections into the ends of the corner posts 4, thereby providing a strong and rigid crate.

Although I have illustrated one of the preferred embodiments of my invention, it will be evident that various slight changes and alterations might be made in the general form and arrangements of the parts described without departing from the invention, and hence I do not wish to limit myself to the precise details set forth, but shall consider myself at liberty to make such slight changes and alterations as fairly fall within the spirit and scope of the appended claim.

I claim:

A crate comprising side walls, end posts rigidly connected to the inner sides of the side walls, top and bottom cross pieces straddling the side walls at opposite ends of the latter, vertical slats nailed at their upper and lower ends to the inner sides of the top and bottom cross pieces at each end of the crate, and nails pivotally securing the opposite ends of the cross pieces to the opposite ends of the posts, the axes of such pivots being spaced from the inner sides of the side walls a distance equal substantially to the thickness of said slats.

GEORGE A. MCLEAN.
